(57) **CLAIM**

The ornamental design for pair of reins, as shown and described.

DESCRIPTION

FIG. 1 is a top plan view of a pair of reins showing my new design.

FIG. 2 is a bottom view thereof.

FIG. 3 is a side elevational view thereof, with the opposite being a mirror image.

FIG. 4 is an enlarged view of the encircled portion of the pair of reins shown in FIG. 1.

FIG. 5 is an enlarged view of the encircled portion of the pair of reins shown in FIG. 2.

FIG. 6 is an enlarged view of the encircled portion of the pair of reins shown in FIG. 3; and,

FIG. 7 is a perspective view of the pair of reins shown in a configuration of use.

The broken lines in FIGS. 1-3 and 7 depict portions of the pair of reins that form no part of the claimed design. The remaining broken lines in FIG. 7 depict environmental subject matter, specifically a horse, that forms no part of the claimed design.

The pair of reins is shown with a symbolic break in its length. The appearance of any portion of the article between the break lines forms no part of the claimed design.

The long dash dot lines in FIGS. 1-6 are for the purpose of depicting the boundary lines of the enlarged views and form no part of the claimed design.
